United States Patent Office

Des. 186,092

Patented Sept. 8, 1959

186,092

COMBINED KEYCASE AND ARTICLE HOLDER

Sidney Schwartz, New York, N.Y., assignor to Bantam-Lite, Inc., Hempstead, N.Y., a corporation of New York

Application October 1, 1956, Serial No. 43,162

Term of patent 14 years

(Cl. D87—3)

Fig. 1 is a rear elevational view of a combined keycase and article holder showing my new design, the article being shown in phantom for illustrative purposes only.

Fig. 2 is a front elevational view thereof as shown in Fig. 1.

Figs. 3 and 4 are top plan and left side elevational views, respectively, thereof, as shown in Fig. 1, and

Fig. 5 is a rear elevational view thereof with the key compartment in open position and the articles shown in broken lines for illustrative purposes only.

I claim:

The ornamental design for a combined keycase and article holder, as shown and described.
